Farnum F. Worsey

UNITED STATES PATENT OFFICE.

THOMAS L. LEE, OF ROCHESTER, NEW YORK, ASSIGNOR TO NORTH EAST ELECTRIC COMPANY, OF ROCHESTER, NEW YORK, A CORPORATION OF NEW YORK.

TERMINAL BLOCK.

1,412,083.

Specification of Letters Patent. Patented Apr. 11, 1922.

Application filed February 17, 1921. Serial No. 445,795.

To all whom it may concern:

Be it known that I, THOMAS L. LEE, a citizen of the United States, residing at Rochester, in the county of Monroe and State 5 of New York, have invented certain new and useful Improvements in Terminal Blocks; and I do hereby declare the following to be a full, clear, and exact description of the invention, such as will enable others skilled 10 in the art to which it appertains to make and use the same.

This invention relates to means for mounting and insulating the terminals and the fuse used in connection with a dynamo-electric 15 machine.

In connection with the dynamo used on a motor-vehicle, it is common to use a fuse, which is usually mounted on the frame of the machine at some convenient point. The 20 object of the present invention is to produce a simple, compact and convenient arrangement wherein the fuse-mounting and the insulating supports for the terminals of the dynamo are combined in a unitary member, and the parts are so brought together 25 that they are readily accessible and conveniently located for connection with the internal conductors of the dynamo.

To the foregoing end the invention consists in the terminal-block hereinafter described, as it is defined in the annexed claims.

In the accompanying drawings Fig. 1 is a plan-view of a terminal-block embodying the present invention, and Fig. 2 is a section on 35 the line 2—2 in Fig. 1, showing also a part of the frame of the machine on which the block is mounted.

The invention is illustrated as embodied in a terminal-block comprising an integral 40 body of insulating material, preferably moulded of bakelite or other plastic substance. This body comprises a base-portion 5 which is suitably shaped, on its inner or lower surface, to rest on the frame of the 45 dynamo.

Rising from the middle part of the outer 50 face of the base-portion 5 are two side-walls 6 connected, at one end, by an end-wall 7. These three walls provide a fuse-receptacle, 55 which is open at one end to facilitate the removal of the fuse.

From the inner face of the base-portion depend two cylindrical projections 8, in 60 which are fixed or embedded the terminals 20 of the dynamo. These terminals are in

the form of tubes with threaded perforations, and, in combination with screws 9 and 10 each terminal constitutes two binding-posts accessible, respectively, from the outside and the inside of the dynamo-frame. 60

Fixed in the fuse-receptacle are clips 11, of any ordinary or suitable form, for retaining the fuse 12, and each of these clips may be provided with an inwardly-projecting binding-post 13, to which an interior conductor of the machine may be connected by means of a screw 14. Between the two fuse-clips the insulating body is secured to the dynamo-frame 21 by means of a screw 15. 70

In Fig. 2 the terminals 20 are shown as connected, by wires 16, to the windings or other parts of the dynamo within the frame 21, while one of the fuse-clips is connected, by a strap 18, with one of the terminals. 75 The connections to the other fuse-clip are not shown. The outer binding-posts serve for the attachment of wires 17 by which the dynamo is connected with other apparatus. 80

In addition to the walls 6 and 7 already described, the terminal-block is provided with walls 19 projecting laterally from the walls 6 near the open end of the fuse-receptacle. These walls 19 not only provide enclosures for the binding-posts, thus improving the resistance of these parts, but they also brace the walls 6 at points where they would otherwise be weak. 85

The invention is not limited to the details 90 of construction of the illustrated embodiment, but may be embodied in various other forms within the scope of the following claims.

The invention claimed is:

1. A terminal-block, for a dynamo-electric machine, comprising: an integral body of insulating-material, consisting of a base-portion formed to seat upon the frame of the machine, and walls rising from the base-portion and forming a fuse-receptacle; fuse-clips mounted in the fuse-receptacle; binding-posts on the outer face of the base-portion at the sides of the fuse-receptacle; and binding-posts on the inner face of the base-portion and connected with the fuse-clips and the outer binding-posts, respectively. 100

2. In combination with the frame of a dynamo-electric machine: an integral body of insulating-material consisting of a base- 110

portion formed to seat on the outer surface of the frame, walls rising from the outer face of the base-portion and forming a fuse-receptacle, and inward projections extending through openings in the dynamo-frame; 5 fuse-clips in the fuse-receptacle; binding-posts on the outer face of the base-member, at the sides of the fuse-receptacle; and terminal-members connected with the binding- 10 posts and extending through said inward projections of the insulating material and accessible at the interior of the dynamo-frame.

3. A terminal-block, for a dynamo-electric 15 machine, comprising: an integral body of insulating-material, consisting of a base-portion formed to seat on the frame of the machine, two side-walls and an end-wall rising from the base-portion and providing a fuse- 20 receptacle open at one end, and a pair of laterally-extending walls projecting from

each side-wall of the fuse-receptacle at the open end of the fuse-receptacle; a binding-post mounted between each of said pairs of laterally-extending walls; and fuse-clips 25 mounted in the fuse-receptacle.

4. A terminal-block, for a dynamo-electric machine, comprising: an integral body of insulating-material, consisting of a base-portion formed to seat on the frame of the 30 machine, two side-walls and an end wall rising from the outer face of the base-portion and providing a fuse-receptacle open at one end, a wall extending laterally from each side-wall near the open end of the fuse-receptacle, and projections from the inner face of the base-portion, at the sides of the fuse-receptacle; and terminal members through said projections and accessible at both faces of the base-portion. 35

THOMAS L. LEE.
